Attorney.

UNITED STATES PATENT OFFICE.

RALPH B. WILSON, OF CHICAGO, ILLINOIS.

LOOSE-LEAF BINDER.

SPECIFICATION forming part of Letters Patent No. 729,476, dated May 26, 1903.

Application filed February 24, 1903. Serial No. 144,722. (No model.)

To all whom it may concern:

Be it known that I, RALPH B. WILSON, a citizen of the United States, residing at Chicago, in the county of Cook and State of Illinois, have invented certain new and useful Improvements in Loose-Leaf Binders; and I do declare the following to be a full, clear, and exact description of the invention, such as will enable others skilled in the art to which it applies to make and use the same, reference being had to the accompanying drawings, and to the letters of reference marked thereon, which form a part of this specification.

This invention relates to new and useful improvements in temporary binders; and it consists in the provision of a novel device whereby the covers of the binder may be adjusted nearer together or farther apart for the purpose of accommodating a small or large number of papers.

More specifically, the invention consists in the provision of two plates which slide in contact with each other, said plates being fastened together by toggle-link connection, and in the provision of an adjusting-screw which passes through links of the connection and so arranged that by turning the threaded shaft the plates may be thrown away from each other or nearer together, suitable guide-rods being provided, which are carried by the plates and telescope within each other in pairs.

The invention consists, further, in various details of construction and in combinations and arrangements of parts, which will be hereinafter fully described and then specifically defined in the appended claim.

My invention is clearly illustrated in the accompanying drawings, which, with the letters of reference marked thereon, form a part of this application, and in which drawings—

Figure 1 is a vertical sectional view through my temporary binder. Fig. 2 is a sectional view taken on line 2 2 of Fig. 1. Fig. 3 is a sectional view longitudinally on line 3 3 of Fig. 2. Fig. 4 is a detail view showing the key attached to the end of the adjusting screw-threaded rod, and Fig. 5 is a sectional view on line 5 5 of Fig. 4.

Reference now being had to the details of the drawings by letter, A and A' designate two angle-plates, one of said plates, A', having a flange A² at each end adapted to form a

guideway in which the plate A slides as the two plates are moved in opposite directions. Each of said plates has a bar B with angled ends secured to the inner face of its right-angled projection, and the ends of said bars, which are bent in opposite directions, are adapted to slide in contact with each other in the guideways C C, which are formed out of pieces of metal which are bent in the shape illustrated in Fig. 3 of the drawings. A rod D, having right threads D' on one end and left threads D² on its other end, is journaled at one end in one of the plates C, as at E, Fig. 3, and its other end, which has a cap or headed screw fitted in the end thereof, is journaled in the opposite plate C, as at E', Fig. 3. Said rod D also passes through slots in the angled ends of the bars B, as shown in Fig. 3. Passing diametrically through one end of said rods D is a pin D', a detail view of which is shown in Fig. 4 of the drawings, said cross piece or pin being provided for the purpose of allowing the hole for the key F, which has diametrically opposite slots in its chambered end and provided for the purpose of rotating the shaft in one direction or the other, accordingly as it is desired to have the covers brought nearer together or farther apart. Projecting from the inner faces of said bars B are lugs B', there being shown in the drawings two of these lugs on each plate or bar, and each of said lugs has an eye adapted to receive a pivotal pin H, on which the outer ends of the links K are pivotally mounted, the inner ends of each link K being pivoted to the link N, which has a centrally-threaded aperture adapted to be fitted over one or the other of the threaded portions of the rod D. Projecting from one of the bars B are the hollow posts M, which are adapted to telescope over the posts M', which project from the opposite bar B, said telescoping rods being provided for the purpose of receiving and holding the papers which are to be bound together. Fasted to the outer faces of the angled portions of said bars B are the base portions Q, to which the covers Q' are hinged at points R.

In operation the two plates, which are connected together by means of the toggle-links, may be thrown from or toward each other by rotating the shaft D by means of the key F in one direction or the other, adapting the

binder to receive a greater or less number of papers, as may be desired.

While I have shown a particular detailed construction of apparatus illustrated in my invention, it will be understood that I may make alterations in the various details of construction of the binder without departing from the spirit of the invention.

Having thus fully described my invention, what I claim as new, and desire to secure by Letters Patent, is—

A temporary binder comprising two angle-plates, one of which has its ends turned to form flanges to receive the other plate and hold the same together, bars with angled ends fastened to the flanged portions of said plates,

metallic guideways in which the ends of said bars are guided, toggle-link connections between said bars, an adjusting-screw having right and left threads mounted in said toggle-links, and passing through the ends of the bars, telescoping posts carried by said bars, and means whereby the screw may be rotated in one direction or the other to throw said plates nearer together or farther apart, as set forth.

In testimony whereof I hereunto affix my signature in presence of two witnesses.

RALPH B. WILSON.
